UNITED STATES PATENT OFFICE.

BENJAMIN E. LAWRENCE, OF CHICAGO, ILLINOIS.

MENU-CARD HOLDER.

Application filed July 13, 1922. Serial No. 574,860.

To all whom it may concern:

Be it known that I, BENJAMIN E. LAWRENCE, a citizen of the United States of America, and a resident of Chicago, county 5 of Cook, State of Illinois, have invented a new and useful Improvement in Menu-Card Holders, of which the following is a specification.

This invention relates to loose leaf holders and particularly holders for menu cards and the like, such as shown in Patents 970,399, September 13, 1910, and 1,014,908, January 16, 1912, issued to Walter H. Sawyer.

The main object of this invention is to provide a menu card holder including hinged cover members having an improved form and arrangement of fastening means of simple and durable construction for detachably securing thereto a folded menu card which is formed at its crease to cooperate with the fastening means.

An illustrative embodiment of this invention is shown in the accompanying drawings, wherein—

Fig. 1 is a plan of a menu card holder embodying this invention, showing the cover members in open position.

Fig. 2 is an enlarged top view of the holder showing a leaf inserted therein.

Fig. 3 is an enlarged view in elevation of the improved fastening means.

In the form shown, the holder includes a pair of cover members hinged to a back, on 35 which is mounted improved fastening means in the form of hooks, which are arranged for engagement with apertures in the crease of a folded menu card to be inserted between the cover members. The cover members are preferably formed to provide 40 frames for supporting advertising cards and menu cards containing lists of special items in addition to those which appear on the folded menu card.

Referring to the drawings, the holder 45 comprises a pair of cover members 1 hinged to a back 2, on which is mounted a pair of fastening hooks 3, for engagement with apertures 4 formed in the crease of a folded menu card 5 to be inserted in the holder.

As illustrated, each of the cover members 50 comprises channel-shaped sections 6 and 7 which are secured together by rivets 8 and arranged to form a frame for a pair of celluloid or other transparent sheets 9 for enclosing an advertising card or a special

menu card, not shown, which is adapted for insertion between the celluloid sheets. The edges of the transparent sheets 9 and advertising card are seated in the channel sections 6 and 7 and are secured against displacement by rivets 10 extending through the section 7.

The frame sections 7 are formed with tubular parts 11 arranged to receive a pair of 65 U-shaped pivot pins 12 for pivotally connecting the covers 1 to the back 2.

In the form shown, the back 2 comprises a narrow flat strip of metal having its ends rounded and extending slightly beyond the 70 upper and lower edges of the cover members 1. The projecting rounded ends of the back 2 prevent the sharp inner corners of the channel sections 6 from coming in contact with and marring the surface of the 75 table or other support on which the holder may be placed. Formed in the back 2 adjacent its ends, are a pair of apertures 13, through which extend the U-shaped pivot pins 12 in oppositely disposed relation so 80 that their ends extend inwardly into the tubular parts 11 of the cover sections 7. This arrangement of the pivot pins 12 permits the cover members 1 to be folded upon each other in either direction without injury to 85 the parts.

As illustrated, the fastening hooks 3 are formed integral with the back 2 and are arranged adjacent opposite ends thereof, with the free ends of the hooks pointed toward 90 one end of the back 2, so as to permit the apertures 4 of the loose leaf 5 to pass over both hooks by a substantially straight line movement of the leaf. The inner edges of the hooks 3 are spaced from the back 2 to 95 form retaining parts 14, which are curved slightly to facilitate the insertion of the leaf.

In order to secure the leaf against removal from the holder without either tearing or distorting the leaf, locking shoulders 15 are formed on the inner ends of the hooks 3 in spaced relation to the back 2. The shoulders 15 are spaced farther from the back 2 than the retaining parts 14, so 100 that, when the leaf is held between the back 2 and the retaining parts 14 of both hooks, 105 it cannot be slipped over the shoulders 15 without distorting it sufficiently at both hooks to lift the leaf over both shoulders 110 simultaneously.

This form of fastening means is simple

and durable in construction and effective and overcomes the necessity for the use of the objectionable elastic bands which have heretofore been used for securing the menu 5 cards to the holder.

The operation of inserting a loose leaf into the holder is believed to be clear from the foregoing description.

Although but one specific embodiment of 10 this invention has been herein shown and described, it will be understood that certain details of the construction shown may be altered or omitted without departing from the spirit of this invention as defined by the 15 following claims.

I claim:

1. A loose leaf holder comprising a back having a pair of cover members hinged thereto, and a pair of hooks on said back 20 for engagement with apertures in a leaf to be inserted in the holder, both of said hooks being disposed in a single plane, said hooks being spaced apart longitudinally of said back and having their free ends pointed in 25 the same direction so as to permit the leaf to be inserted by movement in the opposite direction and be held between said hooks and back.

2. A loose leaf holder comprising a back 30 having a pair of cover members hinged thereto, and a pair of spaced hooks rigidly mounted on said back for engagement with apertures in a leaf to be inserted in the holder, both of said hooks being disposed entirely in a single plane, said hooks extending longitudinally of said back and having their free ends spaced from the back and 35 pointed toward one end thereof so as to permit the leaf to be inserted by movement 40 in the opposite direction and be held between said hooks and back.

3. A loose leaf holder comprising a back having a pair of cover members hinged thereto, a pair of hooks extending longitudinally of said back for engagement with 45 apertures in a leaf to be inserted in the holder, both of said hooks being located entirely in a single plane disposed longitudinally of said back, said hooks having their

free ends pointed in the same direction and 50 spaced from said back to form guides to permit the leaf to be inserted by movement in the opposite direction and be held between said hooks and shoulders formed on the opposite ends of said hooks 55 and arranged to secure the leaf against accidental disengagement from said hooks.

4. A loose leaf holder comprising a back having a pair of cover members hinged thereto, a pair of spaced hooks arranged on 60 said back for engagement with apertures in a leaf to be inserted in the holder, the inner edges of said hooks being formed to provide retaining parts in spaced relation to said back, said retaining parts being disposed in the same plane, the free ends of 65 said hooks being pointed in the same direction and arranged to guide the leaf for insertion between said retaining parts and back, and shoulders formed on the opposite 70 end of said hooks, said shoulders being spaced farther from said back than said retaining parts so as to secure the leaf against accidental disengagement from said hooks.

5. A menu card holder comprising a back, 75 a pair of U-shaped pivot pins extending through said back adjacent its ends, a pair of hinged cover members mounted on said pivot pins, a pair of spaced hooks rigidly mounted on said back for engagement with 80 apertures in a leaf to be inserted in the holder, the inner edges of said hooks being formed to provide retaining parts in spaced relation to said back, said retaining parts being located in a single plane disposed longitudinally of said back, the free ends of 85 said hooks being pointed toward one end of said back and being arranged to form guides for guiding the leaf for insertion between said retaining parts and back, and shoulders formed on the opposite end of said hooks, 90 said shoulders being spaced farther from said back than said retaining parts so as to secure the leaf against accidental disengagement from said hooks.

Signed at Chicago this 10 day of July, 95
1922.

B. E. LAWRENCE.
